Primary Examiner — Cynthia Ramirez*(74) Attorney, Agent, or Firm* — TraskBritt, P.C.**(57) CLAIM**

The ornamental design for a wheel, as shown and described.

DESCRIPTION

The application is also related to U.S. patent application Ser. No. 29/419,172, filed Apr. 25, 2012, now U.S. Pat. No. D676,214, the contents of the entirety of which is also incorporated herein by this reference.

FIG. 1 is a perspective view of a wheel showing our new design;

FIG. 2 is a side view thereof;

FIG. 3 is a front view thereof;

FIG. 4 is a top view thereof; and,

FIG. 5 is the other side view thereof.

The dash-dot-dot broken lines in the figures are for the purpose of illustrating portions of the wheel and form no part of the claimed design.
